(57) **CLAIM**

The ornamental design for a golf cart head cover as shown and described.

DESCRIPTION

The patent or application file contains at least one drawing executed in color. Copies of this patent or patent application publication with color drawing(s) will be provided by the Office upon request and payment of the necessary fee.

1.1 is a front elevation view of a golf cart head cover embodying our new design;

1.2 is a rear elevation view thereof;

1.3 is a right side elevation view thereof;

1.4 is a left side elevation view thereof;

1.5 is a top plan view thereof;

1.6 is a bottom plan view thereof;

1.7 is a bottom, rear and left side perspective view thereof; and

1.8 is a top, front and right side perspective view thereof.

**1 Claim, 8 Drawing Sheets
(8 of 8 Drawing Sheet(s) Filed in Color)**
